(57) **CLAIM**

The ornamental design for a ergonomic frosting applicator nozzle, as shown and described.

DESCRIPTION

FIG. 1 is a perspective view of ergonomic frosting applicator nozzle showing my new design;

FIG. 2 is a side elevational view of the ergonomic frosting applicator nozzle of FIG. 1, the other side being identical thereto;

FIG. 3 is a top plan view ergonomic frosting applicator nozzle of FIG. 2;

FIG. 4 is a bottom plan view thereof;

FIG. 5 is a front elevational view ergonomic frosting applicator nozzle of FIG. 2; and,

FIG. 6 is a rear elevational view of the ergonomic frosting applicator nozzle.

The broken lines are for illustrative purposes only and form no part of the claimed design.
